DESIGN FOR A STIRRER

Harry Bennett, New York, N. Y.

Application February 1, 1936, Serial No. 60,944

Term of patent 3½ years

To all whom it may concern:

Be it known that I, Harry Bennett, a citizen of the United States, residing in New York, in the county of New York and State of New York, have invented a new, original, and ornamental Design for a Stirrer, of which the following is a specification, reference being had to the accompanying drawing, forming part thereof, and in

which Fig. 1 is a perspective view of the stirrer, showing my design; and Fig. 2 a bottom plan view of the casing portion thereof showing my design.

I claim:

The ornamental design for a stirrer, as shown.

HARRY BENNETT.
